(57) **CLAIM**

The ornamental design for a cap, as shown and described.

DESCRIPTION

FIG. 1 is a top view of the cap showing my new design.

FIG. 2 is a bottom view thereof.

FIG. 3 is a front view thereof, shown at an enlarged scale.

FIG. 4 is a left view thereof.

FIG. 5 is a right view thereof.

FIG. 6 is a back view thereof.

FIG. 7 is a perspective view thereof; and,

FIG. 8 is another perspective view thereof.

The broken lines in the drawings illustrate the portions of the cap that form no part of the claim.
